(57) **CLAIM**

The side stripe design for active wear, as shown and described.

DESCRIPTION

FIG. 1 is a left side perspective view of the invented side stripe design for active wear showing my new design.

FIG. 2 is a right side perspective view thereof.

FIG. 3 is a front elevation view thereof.

FIG. 4 is a rear elevation view thereof.

FIG. 5 is a right side elevation view thereof.

FIG. 6 is a left side elevation view thereof; and,

FIG. 7 is a close up right side elevation view thereof.

The portions shown in dashed lines are to show an environment in which the invented design is used, but which do not form part of the design.

The dash-dot-dash broken line(s) define the bounds of the claimed design and form no part thereof.
